NEEDLE WEAVING LOOM

Raymond Dewas, Amiens, France

Application November 3, 1937, Serial No. 172,502
In France November 21, 1936

3 Claims. (Cl. 139—123)

This invention has for its object improvements in the means for guiding the needles, described in my prior Patent No. 2,125,894 in the case in which each of these needles or weft inserting devices is driven through the instrumentality of a propelling device formed by a flexible band secured to the said inserting device and actuated in an appropriate known manner, for example, by means of driving wheels having teeth or projections meshing with perforations provided on the band.

The present improvements have mainly for their object to provide, by means which are simple and readily adaptable to weaving looms, a guiding of the propelling device in the four principal opposed directions two by two, inside the channel receiving the inserting device as it issues from the shed, as well as in the shed when it propels the inserting device therein. The aggregate of the guiding means thus obtained by their combination with those provided in my prior patent, produces a reliable operation of this type of inserting device having a non-rigid propelling device, and permits of very high speed operation.

Embodiments of said improvements are described hereinafter and diagrammatically illustrated, merely by way of non-limitative examples, in the accompanying drawings in which:

Fig. 1 is an overall view, on a small scale, in elevation, of the front part of a slay of an improved weaving loom, the weft inserting devices, or needles, being shown in the position they occupy in the middle of the shed during the change of the thread;

Fig. 2 is a fragmentary view, in elevation, of the said slay, showing one of the inserting devices during its travel in the shed;

Fig. 3 is a view in longitudinal section along 3—3 (Figs. 5, 6 and 7), showing the inserting device in its receiving channel;

Fig. 4 is a view in transverse section along 4—4 (Fig. 2);

Figs. 5, 6 and 7 are views in transverse section along 5—5, 6—6, and 7—7 (Fig. 3) respectively;

Fig. 8 is a similar view to Fig. 7 and shows a flat needle;

Figs. 9 and 10 are similar views to Figs. 4 and 7, respectively, showing a modification;

Fig. 11 is a similar view to Fig. 10, showing a flat needle;

Fig. 12 is a similar view to Figs. 4 and 9, showing another modification;

Figs. 13 and 14 are views in horizontal sec-

tion along 13—13 of Fig. 9 and show two of the bulged shapes the guides may have.

Fig. 15 is a sectional view, similar to Fig. 10, showing improvements in the method of propelling the inserting device; and

Fig. 16 is a sectional view, similar to Fig. 8, showing other improvements in the method of propelling the inserting device.

Each of the inserting devices 1 (one of which conveys the thread, which unwinds from a large fixed weft bobbin, to the middle of the shed where the other inserting device grasps it and pulls same to the other edge of the cloth) is mounted at the end of a flexible band 14 actuated in known manner by a wheel having teeth or projections 15 which is driven alternately in both directions by the crankshaft, for example, through the intermediary of an appropriate drive of any known kind, and meshing with perforations 16 provided in the said band. This latter is fixed towards the front end of the inserting device 1 by means, for example, of rivets 17 passing through a sole 18 provided under the lower face of the arm of the inserting device. The band 14 passes through the lower wall of the channel 8 in a slot 19 and engages in a curvilinear passage 20 which is fixed, on the one hand to the channel 8, and on the other hand to the lower shaft 32.

According to the invention, the guides 13 provided on the front portion of the slay for guiding the arm of the inserting device 1 in the shed, are adapted to ensure at the same time the guiding of the flexible band 14. For this purpose, each of them is provided with a notch 21 and the aggregate of said notches 21 of the series of guides 13, in combination with the notches 21' of a complementary series of guides 13' arranged opposite the former (and in this case the lower part of the notches 21 and 21' may consist of one piece) or in staggered relation to same, effects a guiding of the flexible band 14 in the four principal opposed directions two by two (Fig. 4). Furthermore, the guides 13 and 13' are utilized to ensure the guiding, in the four directions, of the sole 18 interposed between the arm of the inserting device 1 and the flexible band 14. Said sole 18, thus held in the four directions by the guides 13 and 13', forms in this manner an additional guiding and stabilizing means for the inserting device 1 when the latter is in the shed.

As regards the guiding of the band 14 in the channel 8, this is effected, likewise in the four principal opposed directions two by two, by means of a groove 22 of which the upper edges are,

furthermore, utilized for guiding the sole 18 (Fig. 7). The slot 19 (Fig. 6), like the groove 22, also follows the shape of the cross-section of the band 14.

5 The flat needle shown in Fig. 8 has guide elements similar to those of the needle shown in Figs. 2 to 7, but formed in one piece instead of being separate, the lower part of the channel 8 (the upper part of which is eliminated) being 10 likewise shaped accordingly.

As regards the modification shown in Figs. 9 and 10, it is distinguished from the previous embodiments by the fact that the band 14 is arranged laterally, and as it is fixed under the 15 horizontal wing of the guide strip 3 placed along the lower portion of the arm of the needle 1. In this case the guides 13, in addition to their function of guiding the strip 3, furthermore ensure, by means of their groove 24, the guiding 20 of the flexible band 14 in the four principal opposed directions two by two; and still further, by means of their groove 25, they also ensure the guiding of the sole 18' of the needle arm 1 in three directions; in case of necessity it can 25 be guided in four directions. The channel 8 (Fig. 10) is provided with grooves 26, 27 for guiding the band 14 and the sole 18'.

As to the flat needle shown in Fig. 11, it has the same guide elements; the channel 8 being 30 shaped accordingly.

The inserting device 1 shown in Fig. 12 has, in addition to the guide strip 3, another guide strip 3'' located on the reed side. By means of the guides 13 and 13', the inserting device 1 35 as well as the band 14 are guided in the four directions. In the portion where it is no longer covered by the inserting device, the band 14 is widened until it takes up, in the notches 21 and 21' of the guides 13, 13', the place which was 40 occupied by the strips 3 and 3'', so that the band 14 is guided over its whole length in the four directions. This form of inserting device can utilise a channel 8 of which the upper part is eliminated.

45 The bulged guide sections shown in Figs. 13 and 14 show respectively a guide of which the maximum thickness of the bulge is located approximately opposite the main apex 13° (Fig. 9), and a guide of which the bulge forms the edge 50 opposite the fell of the cloth. The opening caused in the lower sheet of the divided warp threads by the introduction of the main apex 13° of such bulged guides is distinctly greater, so that the secondary apex 13' then penetrates 55 in its turn between the warp threads with a further increased safety (as regards the satisfactory division of the threads), and this advantage is obtained without increasing the angle formed by the said threads between the reed and 60 the guides.

As regards the band 14, it is preferably formed by two or more superposed bands made of a flexible and light material preferably such as that known in the trade by the name of 65 "Leatheroid", and having the advantage of operating without lubrication and of offering a very great resistance to wear on contact with the guides 13 which are preferably made of nitrided steel. The said superposed bands are only 70 secured to each other at the spot where they are fixed by the rivet or rivets 17, to the front part of the lower face of the inserting device 1, whereas over the remainder of their length they are not secured to each other, thereby giving 75 the advantage of enabling them to move rela-

tively to each other in the curved portions. A metal band, made of steel for example, can likewise be interposed between two flexible bands made of such a material.

As regards the propulsion of the inserting device, instead of a single wheel 15 having projections as shown in Fig. 3, two wheels can be provided placed one after the other and meshing in the same row of perforations, or again placed one beside the other, the band 14 having in that case 1 two parallel rows of perforations.

According to the improved method of propulsion shown in Fig. 15, the band 14 which is arranged laterally and fixed under the strip 3, is driven by the wheel 15 meshing with the perforations 16, and a second wheel 23 fast on the same shaft 29 meshes, when the inserting device 1 is in the channel 8, with a series of recesses 28 provided in the sole 18'. This arrangement has the advantage that at high speeds it relieves the band 2 when the inserting device starts operating as it issues from the channel 8 and when it slows down as it enters back into said channel.

For the same purpose, and also for avoiding any tendency of the inserting device 1 to be lifted under the effect of the under drive by the wheel 15, there is provided, according to the method of propulsion shown in Fig. 16, an upper driving wheel 15' engaging with recesses 30 provided on the upper face of the inserting device 1.

Finally, likewise for the same purpose, the projections or teeth of the driving wheel 15 of the band can be made to project beyond the thickness of the said band, the said projections engaging in recesses 31 provided in the element 35 located above the said band and formed either by the sole of the inserting device 1, or by the strip 3.

If necessary, a pressure roller can be simply provided, instead of the upper driving wheel 15'.

Naturally certain of the improvements which are the object of the present application can also be applied to the guiding device of the inserting devices of the kind described in the main patent.

It is of course understood that without exceeding the scope of the invention, modifications and improvements of details can be imagined, and also that the use can be considered of means forming the equivalents of those given as examples.

I claim:

1. A needle-guiding mechanism for looms, comprising the combination with a shed, an inserting device movable across the shed, a slay, means connected to said slay and constituting a channel for the inserting device, said channel being positioned adjacent that side of the shed where the inserting device enters, and means connected with said slay and disposed in the front part thereof for the guiding of the inserting device during its travel across the shed; of a flexible propelling member connected with said inserting device, means constituting a part of the first-mentioned means and forming a lower-channel wall having a groove formed therein for the guiding of said flexible propelling member to prevent lateral and vertical movement, and means constituting a part of the second-mentioned means for guiding said flexible propelling member to prevent lateral and vertical movement.

2. A needle-guiding mechanism for looms, comprising the combination with a shed, an inserting device movable across the shed, a slay, means connected to said slay and constituting a channel for the inserting device, said channel being positioned adjacent that side of the shed where

the inserting device enters, and means connected with said slay and disposed in the front part thereof for the guiding of the inserting device during its travel across the shed; of a flexible propelling member comprising at least two superposed bands made of a non-metallic flexible material, means connecting said bands to said inserting device, said bands being secured to each other only at the place where they are connected to the inserting device, means constituting a part of the first-mentioned means and forming a lower-channel wall having a groove formed therein for the guiding of said flexible propelling member to prevent lateral and vertical movement, and means constituting a part of the second-mentioned means for guiding said flexible propelling member to prevent lateral and vertical movement.

3. A needle-guiding mechanism for looms, comprising the combination with a shed, an inserting device movable across the shed, a slay, means connected to said slay and constituting a channel for the inserting device, said channel being positioned adjacent that side of the shed where the inserting device enters, and means connected with said slay and disposed in the front part thereof for the guiding of the inserting device during its travel across the shed; of a flexible propelling member connected with said inserting device, a sole carried by said inserting device, means constituting a part of the first-mentioned means and forming a lower-channel wall having a groove formed therein for the guiding of said flexible propelling member to prevent lateral and vertical movement, and means constituting a part of the second-mentioned means for guiding said flexible propelling member and said sole to prevent lateral and vertical movement, whereby an additional guiding and stabilizing device for the inserting device is provided when the latter is in the shed.

4. A needle-guiding mechanism for looms, comprising the combination with a shed, an inserting device comprising a strip and movable across the shed, a slay, means connected to said slay and constituting a channel for the inserting device, said channel being positioned adjacent that side of the shed where the inserting device enters, and means connected with said slay and disposed in the front part thereof for the guiding of the inserting device during its travel across the shed; of a flexible propelling member connected with said strip, a sole carried by said inserting device, means constituting a part of the first-mentioned means and form-

ing a lower-channel wall having a groove formed therein for the guiding of said flexible propelling member to prevent lateral and vertical movement, and means constituting a part of the second-mentioned means for simultaneously 5 guiding said strip, said flexible propelling member and said sole.

5. The mechanism in accordance with claim 1, comprising a pair of guide strips carried by the inserting device on opposite sides thereof, 10 the means disposed in the front part of the slay for the guiding of the inserting device having notches formed therein for receiving said guide strips, the flexible propelling member having a 15 narrower portion which is connected with the inserting device and a wider portion fitting into said notches when said guide strips are withdrawn therefrom.

6. The mechanism in accordance with claim 1, comprising a driving wheel engaging the flexible propelling member for driving the same, and complementary propelling means engaging the inserting device for driving the same.

7. The mechanism in accordance with claim 1, wherein the flexible propelling member has 25 openings formed therein, and wherein the inserting device has recesses formed therein and situated above at least some of said openings, said mechanism comprising a driving wheel having 30 projections adapted to extend through said openings and into said recesses, whereby the flexible propelling member and the inserting device are directly engaged and actuated by said driving wheel.

8. A needle-guiding mechanism for looms, 35 comprising the combination with a shed, an inserting device movable across the shed, a slay, means connected to said slay and constituting a channel for the inserting device, said channel being positioned adjacent that side of the shed 40 where the inserting device enters, and guides mounted on the front part of the slay for the guiding of the inserting device during its travel across the shed; of a flexible propelling member connected with said inserting device, means constituting a part of the first-mentioned means and forming a lower-channel wall having a 45 groove formed therein for the guiding of said flexible propelling member to prevent lateral and vertical movement, and means constituting a part of the guides for guiding said flexible propelling member to prevent lateral and vertical movement, said guides being of bulged shape in horizontal cross-section.

RAYMOND DEWAS.
